HOLDER FOR THREAD COPS OR BALLS

Filed April 1, 1924

UNITED STATES PATENT OFFICE.

JANE MASTEN POWERS, OF WASHINGTON, DISTRICT OF COLUMBIA.

HOLDER FOR THREAD COPS OR BALLS.

Application filed April 1, 1924, Serial No. 703,431.

To all whom it may concern:

Be it known that I, JANE M. POWERS, a citizen of the United States, and a resident of Washington, in the District of Columbia, 5 have invented certain new and useful Improvements in Holders for Thread Cops or Balls, of which the following is a specification.

My present invention relates generally to 10 holders for thread cops or balls from which it is essential that the thread may feed easily for crocheting and the like, my primary object being the provision of a simple inexpensive device capable of mounting in 15 various different positions and in connection with different articles adapted to its support, whereby a thread cop or ball may be held and prevented from rolling around, for the effective feed of thread used for instance in knitting and crocheting and another object is the provision of a device of 20 this character which is adapted especially to the cylindrical cops of crocheting thread wherein the thread is wound around an 25 axial cylinder.

According to my invention I provide a holder which includes a U-shaped spring wire member, the free ends of which may be extended through the axial tube or cylinder 30 of a cylindrical thread cop together with means with which the spring wire clamp is associated at one end for supporting the clamp and consequently the cop held thereby in a freely outstanding position whose 35 inclination may be easily controlled and whose position permits the thread to feed easily from the free end of the cop.

In the accompanying drawing which 40 illustrates my present invention and forms a part of this specification,

Figure 1 is a perspective view illustrating the practical application of my invention.

Figure 2 is a sectional view therethrough 45 illustrating its application to a slightly different form of support, and

Figure 3 is a perspective view illustrating a slightly modified form adapted to still another character of support.

Referring now to these figures my invention proposes in the first instance a U-shaped clamping member 10 which is preferably 50 formed of spring wire with a coil 11 at one end so as to lend additional resiliency and clamping strength to its elongated extensions

seen at 12 and which are adapted to extend through the axial cylinder or tube 13 of a thread cop 14 of the cylindrical form so commonly used for crocheting thread. The free ends of the extensions 12 of this clamping member are preferably turned outwardly away from one another as indicated at 15 just sufficient to engage the free end of the axial cylinder or tube 13 and avoid all danger of pulling the thread cop off of 60 the clamp 10.

My improved holder also includes a body portion or fulcrum block 16 across which the clamping member 10 is extended adjacent to its coiled end 11, together with means engaging the said coiled end of the clamping member whereby the clamping member is held in a substantially horizontal outstanding position in such manner that its cop receiving portion extends wholly beyond one 70 side of the body member or fulcrum block 16 and its inclination may be varied.

For the above purpose a hook member 17 may be utilized as in Figures 1 and 2, the fulcrum block 16 being formed of a material permitting the hook member 17 to be screwed into one side face thereof so as to engage the coiled end 11 of the clamping member 10 as shown. In the form of the invention shown in Figures 1 and 2 wherein 80 the hook member 17 is utilized for the foregoing purpose, I preferably employ a U-shaped clamp 18 securely fastened by a screw and the like 19 at one end to the lower surface of the body member or fulcrum 85 block 16 and having an adjustable thumb screw 20 threaded through its opposite end so that the holder may thus be clamped in connection with either the arm 21 of a chair 90 22 as in Figure 1 or the edge of a table 23 95 as in Figure 2, the bracket being either turned toward the free ends of the clamp 10 as in Figure 1 or away from the free ends of the clamp as in Figure 2.

According to Figure 3 the body member or fulcrum block 16 may be anchored by the same means utilized to hold the clamping member 10 in the desired outstanding position such means being in the form for instance of a pin fastener 24 extending at 100 one end through the coiled end of the clamping member 10 and engaged at its opposite end with the seat pad for instance as indicated at 25 of a chair or other article of furniture or the mattress of a bed, upon the 105 110

surface of which the body member or fulcrum plug 16 rests adjacent to the connected point of the pin fastener.

It is obvious that while I have shown the body member or fulcrum block 16 of plain rectangular form and the clamping member 10 likewise unembellished, both of these major portions of my improved holder may be suitably ornamented or otherwise formed to present an attractive pleasing appearance and decorated for instance to accord with the articles of furniture or other supports to which the holder is attached in use.

It is also obvious that instead of simply extending the clamping member 10 loosely around the top of the body member or fulcrum block 16 as in Figures 1 and 2, I may mount the extensions 12 of the clamping member through screw eyes 26 and the like spaced apart at the top of the body member or fulcrum block, which will thus prevent any side sway of the cop or thread ball 14 held on the clamping member.

I claim:

25. 1. A holder for thread cops and balls having axial tubes therethrough, including a U-shaped clamping member having a coil at one end, adapted to extend through the axial tube and having the opposite ends thereof outturned to engage the adjacent end of the tube, a body member or fulcrum block across which the clamping member extends adjacent to its coiled end, and means engaging the coiled end of the clamping member to hold the latter in freely outstanding position.
30. 2. A holder for thread cops or balls having axial tubes therethrough, consisting of a clamping member extending through the said tube and projecting therebeyond, a body member or fulcrum block across which the projecting end of the clamping member is held whereby to support the thread cop

or ball in horizontally outstanding position at one side of the body member, and means to hold the body member or fulcrum block in upright position upon a suitable support. 45

3. A holder of the character described including a body member or fulcrum block, a clamping member extending across the upper portion of the said body member and having extensions spaced from one another and projecting beyond one side of the said body member, and means engaging the opposite end of the clamping member at the opposite side of the body member to hold the latter in upright position and also hold the clamping member in substantially horizontal outstanding position with respect to the body member. 50 55

4. A holder of the character described including a U-shaped clamping member having a coil at one end and having elongated extensions curved away from one another at their free ends, a body member or fulcrum block across which the said clamping member extends adjacent to its coiled end, and a pin fastener at one side of the body member or fulcrum block, engaging the coiled end of the clamping member as described. 60 65

5. A holder of the character described including a U-shaped clamping member having a coil at one end and having elongated extensions curved away from one another at their free ends, a body member or fulcrum block across which the said clamping member extends adjacent to its coiled end, and a pin fastener at one side of the body member or fulcrum block, engaging the coiled end of the clamping member, said body member having upstanding guide members receiving the extensions of the clamping member as described. 70 75 80

JANE MASTEN POWERS.
